UNITED STATES PATENT OFFICE

REGINALD J. BENNETT, OF SPOKANE, WASHINGTON

COOLER

Application filed April 22, 1929. Serial No. 357,051.

My invention relates to coolers and more particularly to a cooler that is adapted to be installed in a window frame for the purpose of preserving foods placed therein both in 5 winter and in summer. Certain objects of the invention are to provide means whereby the device may be adjusted to fit window frames of various widths. Further objects are to provide novel ventilator means for the cooler 10 together with other novel features of construction.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

20 Figure 1 is a view in perspective showing the cooler installed in a window frame;

Fig. 2 is a view in transverse vertical section of the same;

Fig. 3 is a view in horizontal section taken 25 substantially on a broken line 3, 3 of Fig. 2; and

Fig. 4 is an enlarged fragmentary view in horizontal section showing the ventilator means.

20 Referring to the drawings throughout which like reference numerals designate like parts, the numeral 5 indicates a window sill, the numeral 6 designates the window frame sides, and 7 indicates the window sash, all of 35 which are of the ordinary and well known construction.

The cooler comprises a bottom 8, a rear wall 9, a top 10, a front wall 11, and end walls 12. Said bottom, rear, top and end walls are preferably made of double metal construction with a filler of ground asbestos, cork or other insulator material 13 placed within said hollow walls for the purpose of maintaining an even temperature within the cooler 45 as will be understood.

The top wall 10 slants downwardly and outwardly for the purpose of draining off the water from rain or snow. The front wall 11 is also made of double metal construction and 50 is provided with an opening for a door 14 that

is hinged at 15 to said wall. Said door provides means for entry in removing or placing articles of food in the cooler and I prefer to make the door with a glass panel so that the 55 contents of the cooler are visible.

The hollow end portions of the front wall 11 have extension wings 16 slidably installed therein and the ends of said wings are provided with flanges 17. Thus, when the device is installed within a window frame, said wings 60 may be extended in accordance with the particular width of the frame and their flanges may be secured to the sides 6 of said frame by means of screws or other fastenings 18.

In the installed position of the cooler as 65 shown in Figs. 1 and 2, its bottom 8 is disposed horizontally with its inner end resting on the sill 5. As shown in Fig. 2, a wedge or bracket may be interposed between said sill and bottom for the purpose of retaining the 70 device more securely in place. The window sash 7 is lowered to engagement with the top 10 of the cooler thus effecting a complete closure of the window.

The means for ventilating the cooler comprises a hole 19 through each end wall 12 thereof and said holes having wire screens 20 for the purpose of excluding flies or other insects. Each of said holes is provided with a disc 21 pivoted at 22 to said walls and a 80 rod 23 is pivoted at 24 to each of said discs. Said rods are each provided with a slot 25 and a pin 26 passing through said slots provides means whereby said rods may be slidably moved back and forth to completely open or 85 close the ventilator holes as shown respectively in dotted or full lines in Fig. 2 of the drawings.

Having thus described my invention, it being understood that minor changes may be resorted to in its construction without departing from its scope or spirit, what I claim and desire to secure by Letters Patent of the United States is:—

The combination with a window frame of a 95 cooler installed therein, said cooler having an outer and an inner spaced wall for its top, bottom, front, rear and ends, insulator material within said spaced walls, an extension wing for each front end portion of the cooler slid- 100

ably disposed between the outer and inner front wall and arranged to be extended outwardly therefrom, flanged end portions for said wings adapted to be secured to the sides of the window frame, the lower front edge of the cooler resting on the window sill and the top front edge engaged by the window sash whereby the window opening is completely closed, a screen opening for either end wall of the cooler, a door pivotally mounted at each opening, a rod pivoted to each door having a slot therein, and a pin for said slot whereby the doors may be pivotally moved to open or close said screened openings by slidable movement of the rods.

In testimony whereof I affix my signature.

REGINALD J. BENNETT.
